DESIGN FOR A CLASP-ON SNAP FASTENER

Halpha G. Johnston, Fort Worth, Tex.

Application September 8, 1945, Serial No. 121,950

Term of patent 14 years

(Cl. D17—11)

To all whom it may concern:

Be it known that I, Halpha G. Johnston, citizen of the United States of America, residing at Fort Worth, in the county of Tarrant and State of Texas, have invented a new, original, and ornamental Design for a Clasp-On Snap Fastener, of which the following is a specification, reference being had to the accompanying drawing, forming part thereof.

Figure 1 is a plan view of a clasp-on snap fastener of my new design.

Figure 2 is an inverted plan view; and

Figure 3 is the side elevational view of the same.

I claim:

The ornamental design for a clasp-on snap fastener, substantially as shown.

HALPHA G. JOHNSTON.
